UNITED STATES PATENT OFFICE.

HENRY J. GAISMAN, OF NEW YORK, N. Y., ASSIGNOR TO AUTO STROP COMPANY, OF NEW YORK, N. Y., A CORPORATION OF NEW YORK.

SAFETY-RAZOR.

1,022,730.

Specification of Letters Patent.

Patented Apr. 9, 1912.

Application filed October 15 1909. Serial No. 522,712.

To all whom it may concern:

Be it known that I, HENRY J. GAISMAN, a citizen of the United States, and resident of New York city, borough of Manhattan, in the county of New York and State of New York; have invented certain new and useful Improvements in Safety-Razors, of which the following is a specification.

The object of my invention is to provide improved means for adjusting the guard of a safety razor toward and from the blade edge, and for holding the guard in positions of adjustment.

In carrying out my invention I provide a frame or support having a handle, a guard or blade seat provided with an extension having two adjacent members pivotally supported, and a worm journaled upon the frame or handle and coacting with said members, whereby the guard may be adjusted with respect to the blade edge and will be retained in set position.

Further details of improvement embraced within my invention will be more fully hereinafter set forth and then pointed out in the claims.

Reference is to be had to the accompanying drawings forming part hereof, wherein,

Figure 1 is a rear view of a safety razor embodying my invention; Fig. 2 is a similar view, parts being broken away; Fig. 3 is a sectional side view; Fig. 4 is a view similar to Fig. 3, showing the parts in a different position; Fig. 5 is a detail perspective of part of the guard or blade seat, and Fig. 6 is a detail section of a modification.

A suitable frame is indicated at 1 and is shown provided with uprights 1^a spaced apart and supporting a rod or shaft 2 to which a suitable blade holder 3 is attached, the arrangement shown being such that a strop may be passed through the frame beneath blade 4. The guard or blade seat 5 may generally be of any suitable construction, and is shown having blade engaging lugs or hooks 5^x and also provided with an extension 5^a that passes through an opening 6^a in handle 6, to have freedom of movement in said opening. Extension 5^a has two adjacent members or branches 5^b, 5^c shown located within handle 6 and provided with a bore or bearing 5^d receiving a pin or rod 7 passing through handle 6, whereby the guard is pivotally supported. The adjacent members or branches 5^b, 5^c may be formed

integral with extension 5^a of the guard by suitably bending the metal, as indicated in Figs. 2, 3, 4 and 5, or the members or branches 5^b, 5^c may be made in separate parts suitably secured together, as by rivet 8, as shown in Fig. 6, one of which parts has the bore or bearing 5^d. The members 5^b, 5^c are provided with alined threaded bores or teeth 9, 9^a receiving the threads of a worm or screw 10, which is shown journaled in bearings upon handle 1 and provided at the outer end with a finger piece 11, which may be provided at its outer corners with projecting ears 11^a for convenience in operating the same by the finger. Worm 10 is shown provided with threads 10^a receiving a nut 12, whereby the worm is rotatively and movably supported. In assembling the parts the members 5^b, 5^c are passed through the opening 6^a and pin 7 is passed through bore 5^d; then the worm is passed through the threads of members 5^b, 5^c and through the bearings in the handle and retained in position.

In using the device, when the worm is rotated in one direction, the guard will be moved forwardly, as in Fig. 4, to release the blade from the hooks or lugs 5^x, whereby the blade may be swung upwardly and removed or replaced, cleaned or stropped, and when the worm is rotated in the opposite direction, the blade being placed upon the guard or seat, the latter will be moved inwardly to retain the blade in position with respect to the guard, as in Fig. 3. As the worm operates simultaneously upon the adjacent members 5^b, 5^c of the guard extension the tendency will be to cause the worm to be held firmly by frictional engagement with the threads 9, 9^a as to retain the guard or blade seat securely in set position by reason of the independent movement permitted the members 5^b, 5^c, as distinguished from the action of a worm in a single nut, whereby looseness between the threads of the nut and the worm or screw might arise.

While I have illustrated a practical embodiment of my invention, it will be understood that changes may be made, within the scope of the appended claims, without departing from the spirit thereof.

In this application I do not broadly claim a guard having an extension pivotally supported by or within the handle and operated by a worm, since that subject matter is embraced in my application for safety

razors, filed September 4, 1909, Serial No. 516,165.

Having now described my invention what I claim is:—

- 5 1. A safety razor comprising a blade support, a guard or blade seat provided with an extension having a pair of adjacent separated members, a pivot supporting said members, and a worm working in threads in said members.
- 10 2. A safety razor comprising a blade support, a blade seat or guard provided with an extension having a plurality of adjacent members provided with alined threads, means to movably support said members, a worm coacting with said threads, and means to retain the blade upon the blade seat or guard.
- 15 3. A safety razor comprising a blade support having a handle provided with an opening, a guard having an extension passing freely through said opening and provided with a plurality of adjacent members, means for movably supporting said members, and a worm working in threads in said members.
- 20 4. A safety razor comprising a frame provided with a pivotally supported blade holder and having a handle provided with an opening, a guard having an extension passing through said opening and provided with a pair of adjacent substantially parallel members, means on the handle pivotally supporting said extension, and a worm working in threads in each of said members.
- 25 5. A safety razor comprising a frame provided with blade supporting means, a guard

having an extension and provided with a pair of adjacent members having a bore at the lower part and alined threaded openings above said bore, a pin entering said bore to 40 pivotally support the guard, and a worm working in the threads of said members.

6. A safety razor comprising a blade support, a guard provided with a pivotally supported extension, and a worm working in 45 threads provided on said extension, said worm having a handle provided with opposed outwardly extending ears spaced apart.

7. A safety razor comprising a frame having a blade support, a guard having an extension passing into the handle and pivotally supported therein, and a worm journaled upon said handle and working in threads upon said extension, said worm having a handle at one end and a nut at the opposite end. 50

8. A safety razor comprising a blade support, a guard provided with blade retaining means, means for pivotally supporting the 60 guard, a worm, means for pivotally supporting the worm, complemental means on the arm coacting with the worm, and means for retaining said worm in set position.

Signed at New York city, in the county of 65 New York and State of New York this 11th day of October, A. D. 1909.

HENRY J. GAISMAN.
